5 Claims. (Cl. 280—112)

This invention relates to a device for tilting the body of vehicles of all kinds, especially of motor vehicles, when negotiating curves. In the case of modern vehicles, in which there is a more or less rigid connection between the body and the underframe the objection becomes apparent, especially in the curves, that the occupants are forced towards one side or the other owing to the centrifugal force. The present day spring arrangements operate in the curves in such a manner, that the body is pressed towards the outer side of the curve, whereas the opposite should actually be the case. To render this possible, link systems are provided according to the invention as connection between the body and the axles, these links being movable transversely to the direction of travel and hingedly connected either indirectly or directly with the body at one end and with the axles or the under frame of the car at the other end. The links are arranged in such a manner that the constant distance between their body joints is smaller than that of the axle joints. When such a vehicle negotiates a curve, the body, owing to centrifugal force and the link arrangement, automatically inclines towards the inner side of the curve, so that the links mounted on this side swing downwards and those on the outer side of the curve lift the body on this side.

30 An embodiment of the invention in which pairs of links are employed for each system is illustrated by way of example in the accompanying drawing in which:—

Fig. 1 is a diagrammatic view showing the link arrangement.

Fig. 2 shows a car in front elevation.

Fig. 3 is a top plan view of the front axle.

Near each end of the axles 1, two pairs of links 2, 3 and 4, 5 are hingedly mounted on pins 6, 7 and 8, 9 respectively. The links 3, 5 are hingedly connected to the bifurcated ends 10, 11 of levers 12, 13 respectively, and these levers are connected to the vehicle body 14 at 15, 16 by pairs of arms 17, 18. Between the bifurcation of the ends 10, 11 of the levers 12, 13 elbow levers 19, 20 respectively are hingedly mounted and carry one end of springs 21, 22 which carry at their other end the arms 17, 18. On the elbow levers 19, 20 pairs of rocker levers 23, 24 are hingedly mounted at one end on pivot pins 25, 26 and pivotally connected at a point intermediate their length to pivot pins 27, 28 carried by the pairs of links 2, 4 respectively. The free ends of the pairs of rocker levers 23, 24 are connected to the axles 1 by tension springs 29, 30 tending to main-

tain the links 23, 24 in alignment with the links 2, 3 which are prevented from moving outwards by stops 31, 32 mounted on the axles 1.

The device operates in the following manner:—

The body 14 is at all times resiliently supported by the springs 21, 22 carried by the arms 17, 18 and the angle levers 19, 20. When the vehicle negotiates a curve the body 14 together with all the hinge connections situated above the axle 10 tends to swing outwards away from the centre of the curve under the action of the centrifugal force, for example in the direction indicated by the arrow F in Fig. 1. This outward movement is, however, prevented for the link 23 by the stop 15 32 which arrests the movement of the links 4 with the result that the rocker levers 11b swing about their pivot pins 28 on these links 4 against the action of the springs 30 and tension these springs. The links 5, however, can swing outwards with the elbow lever 20. As the elbow lever 20 is hingedly connected to the rocker levers 24 by the pivot pins 26 its outward movement is limited by the radius of the arc described by the pivot pins 26 about the pivot pins 28. Consequently the inner end of the lever 13 will be forced to ascend, thereby lifting the side of the body 14 to which it is connected and at the same time raising the centre of gravity. On the other side of the body, that is the side adjacent the inner side of the curve, the link 3 swings inwards together with the elbow lever 19, lever 12 and arm 17 pivoting about its point of connection with the body, so that this side of the body swings downwards and the body is inclined towards the inner side of the curve. As the links 2 carry the rocker levers 23 which are connected to the elbow lever 19 by the pivot pin 25 both the rocker levers 23 and the links 2 will also swing inwards, the levers 23 pivoting about their pins 25 but remaining in alignment with the links 2 as their pivot pins 27 likewise swing inwards. Consequently the springs 21 are not tensioned.

When the curve has been negotiated and consequently the centrifugal force is removed the body 14 will swing back into its horizontal position under the action of gravity causing the links and levers to return into their initial positions. This movement is assisted by the tensioned 45 springs 30 which swing the rocker levers 24 back into alignment with the links 5 exerting a pull on the outer end of the lever 13 through the intermediary of the elbow lever 20.

The fundamental idea of the invention is that 55

the construction can be kept as low as possible, because the centre of gravity may be situated far above the suspension points 15 and 16 (Fig. 1). The desired inclined position is ensured, providing 5 the centre of gravity lies approximately within the triangle e which is formed by an imaginary line connecting the lower points of connection of the links 3 and 5 with the body suspension points 15 and 16 and the extension of these connections. 10 This is very important for motor busses.

It may briefly be stated that the body 14 is connected to the underframe or axles 1 of the vehicle by link systems 12, 3 and 13, 5 divided into two sections 12, 13 connected to the body 14 and 15 3, 5 connected to the axle 1, other link systems 19, 23, 2 and 20, 24, 4 being provided which act on sections 12 and 13 and regulate their movement in accordance with the movement of the sections 3 and 5 to impart the incline to the body 14, the object of the springs 29, 30 being to assist 20 the returning of the sections into their normal position after negotiating a curve. The shorter the parts 12, 13 are made relatively to the parts 3, 5 the more deep will the car body descend when 25 assuming an inclined position.

The distance between the body suspension points 15, 16 always remains constant and also the distance between the pivot points 1, 8 of the links 3, 5.

30 Fig. 1 shows a link system diagram wherein the position assumed by the different parts is indicated in dot-dash lines. All the parts which are unnecessary for the transverse movement are omitted from Fig. 1. In the example illustrated 35 the return movement of the body from the inclined position into its normal position is assisted by the fact that the body is positively lifted during the guiding into the inclined position and with the aid of the centrifugal force and consequently descends and assumes a level position 40 when the centrifugal force ceases to act. Thus, the return springs 29, 30 are not excessively stressed.

If, however, the car body were to descend when 45 assuming an inclined position, the return springs must be stronger in order to bring back the body into its normal position. This would be necessary, for example, if the links 3, 5 were hingedly connected directly with the car body. The parts 50 2, 4, 6, 8, 10 to 13, 15 to 28, 31 and 32 would be superfluous and the return springs 29, 30 must be directly connected with the links 3, 5. The front axle is then preferably connected with the rear axle for maintaining the track width. In the resultant construction there would be no spring suspension to absorb shocks caused by unevennesses 55 in the surface of the road.

It is evident that a vehicle constructed in this manner will, when negotiating curves, behave as 60 above mentioned, namely the body assumes the inclined position shown in Fig. 2, that is quite naturally tilts towards the inner side of the curve.

The body will automatically incline at a greater angle the higher the travelling speed and therefore the centrifugal force is, because an increasing gravity resistance is accompanied by an increasing angle of inclination. The construction presents the further advantage that, when travelling over a surface inclined transversely to the travelling direction, that is on a cambered road surface, the body is always suspended in horizontal position.

I claim:

1. A device for inclining the body of vehicles of all kinds especially motor vehicles, when negotiating curves, comprising in combination with the body and the under frame of the vehicle, two pairs of link systems, each link system comprising at least one bar, one of these pairs of link systems arranged at the rear end and the other at the front end of the vehicle with a link system of each pair adjacent an end of the vehicle axle, the link systems of each pair pivotally connected a constant distance apart at their lower ends to the under frame and at their upper ends to said body at points closer together than the connecting points of the lower ends of said link systems and the body thus supported by said link system, and springs adapted to normally maintain the car body in horizontal position, the axes of the pivotal connections between said links and said body and also between said links and said under frame lying in the longitudinal direction of the vehicle so that said link systems oscillate only in the transverse direction of the vehicle against the action of said springs on the body.

2. A device as specified in claim 1, in which the underframe consists of axles and each link system includes two hingedly interconnected bars and means connected with each of said link systems and with the underframe for guiding and restricting the movements of said link systems.

3. A device as specified in claim 1, in which the underframe consists of axles and each link system includes two hingedly interconnected bars, and pairs of hingedly interconnected rods, each pair of rods being hingedly connected at one end to one of said axles and at its other end to one of said link systems and adapted to guide and restrict the movement of said link systems.

4. A device as specified in claim 1, in which each link system includes a substantially vertical bar and a substantially horizontal bar, said horizontal bar consisting of blade springs.

5. A device as specified in claim 1, in which each link system includes a substantially vertical bar and a substantially horizontal bar, said horizontal bar consisting of blade springs, and means hingedly connected on the one hand with the body and on the other hand with the link system for preventing the edging of said springs.

JOACHIM KOLBE.
